UNITED STATES PATENT OFFICE

EDWARD W. MENKE, OF CHICAGO, ILLINOIS, ASSIGNOR TO ST. REGIS PAPER COMPANY, OF NEW YORK, N. Y., A CORPORATION OF NEW YORK

MOUNTING FOR MERCURY SWITCHES

Application filed March 30, 1929. Serial No. 351,183.

This invention relates to a mounting for a mercury switch and has as its object to provide a mounting whereby the switch may be operated by a slight movement of an operating member, and the parts can be accurately adjusted so that the switch is properly related to its tripping member. Details of the invention will appear as the description proceeds.

10 In the accompanying drawings illustrating one embodiment of the invention, Fig. 1 is a section through a portion of the mounting for a mercury switch, and indicating its relation to a tripping member, the section being taken on the line 1—1 of Fig. 2; Fig. 2 is a plan view of the apparatus shown in section in Fig. 1, with the housing cap removed, as indicated by line 2—2 on Fig. 1; Figs. 3, 4 and 5 are sections on lines 3—3, 4—4 and 20 5—5, respectively on Fig. 2.

The switch and its mounting are shown arranged to be attached to a filling and weighing device or similar apparatus, and to be tripped by a movement of the weighing device.

A housing 10 is provided with a cover 11 for covering the switch and its mounting. Within this housing there is a bracket 12 having arms 13 and 14 pivoted to the housing on 30 screw pivots 15 and 16. The bracket is provided with a tail-piece 17 through which there is a hole 18. A bolt 19 mounted in the housing extends through hole 18. Surrounding bolt 19 there is a spring 20 resting upon 35 the housing and supporting the bracket. A screw 21 mounted in the top of the housing acts as an adjustable stop limiting the upward movement of the bracket. A lock-nut 22 is provided for locking the adjusting screw 40 in position.

A carrier 23 is mounted upon the upper side of bracket 12 and is provided with a slot 24 through which there passes a set screw 25, so that the carrier may be fastened in adjusted 45 position on the bracket.

The carrier is provided with forwardly projecting ears 26. A clamp 27 is provided with a pivot pin 28, the ends of which are mounted in pivot cups 29 screwed through 50 ears 26. A mercury switch 30 is held in posi-

tion on clamp 27 by clips 31. Clamp 27 is provided with an arm 32 having its end split. A screw 33 is adjustable through the split end of arm 32 and rests on the bracket and supports the end of the arm so as to normally 55 maintain the switch at the desired angle. A clamp screw 34 may be provided for tightening the split end of arm 32 on screw 33 so as to hold it firmly in adjusted position.

On the underside of clamp 27 at a point 60 closely adjacent to the pivot rod 28, there is fastened a wear plate 35 in position to be contacted by a trip pin 36 mounted upon a member 37 which may be attached to a weighing device. Member 37 may be extended, if 65 desired, between stop screws 38 to limit the movement of this member.

It will be readily understood that leads 39 from an electric circuit are connected to the mercury switch, so that the mercury closes 70 the circuit through these leads when the switch is in normal position, but the circuit is broken when the switch is tilted by the rising of trip rod 36.

In the use of the device suggested, where 75 it is employed in a filling and weighing machine, the circuit through the switch may control the operation of the feeding means, and the trip rod may be mounted in connection with the weighing means so that when 80 the desired amount of material has been fed into a receptacle, the resultant movement of the weighing device raises rod 36 and tilts the mercury switch so as to open the circuit. The opening of the circuit may result in stopping 85 a motor driving a feeding device, or in closing a gate, or in both.

It will be readily seen that the mounting of the mercury switch as described makes it possible to adjust it so as to obtain the precise action desired. The height of pivot pin 28 may be adjusted by screw 21, as spring 20 raises the bracket and pivot points carried thereby to whatever height is allowed by screw 21. The distance from the axial line 95 of pivots 28 to the point of rod 36 can be controlled by adjusting carrier 23 on bracket 12 by means of slot 24 and screw 25. The angle at which the mercury switch normally rests is readily controlled by adjustment of 100

screw 33. The parts are so related that the switch and clamp return to the switch-closing position by gravity when permitted to do so by the lowering of rod 36.

While one specific embodiment of the invention has been described in considerable detail, it will be readily understood that various changes may be made within the scope of the appended claims.

10 11 What I claim is:

1. In combination, a carrier mounted for adjustment vertically and for independent adjustment horizontally, a mercury switch pivoted on the carrier, and means for adjusting the angle to the carrier at which the switch normally rests.

2. In combination, a carrier mounted for adjustment vertically and for independent adjustment horizontally, a clamping member 20 pivoted on said carrier, a mercury switch clamped on said clamping member, and adjustable means for limiting the oscillation of said member.

3. In combination, a carrier, a clamping member pivoted on the carrier, a mercury switch clamped on said clamping member, a lug on one side of said member, and a set screw adjustably limiting the movement of said lug.

30 4. In combination, a carrier, a clamping member pivoted on the carrier, a mercury switch clamped on said clamping member, a wear plate on the underside of said member adjacent to one side of its pivot, an operating pin adapted to contact said plate and tilt said member in one direction, and a lug projecting from said member and carrying a set screw adapted to limit the tilting of said member in the other direction.

40 5. In combination, a bracket, resilient means tending to raise said bracket, an adjustable stop limiting the raising of said bracket, a mercury switch mounted on said bracket, and a vertically movable member 45 adapted to operate said switch.

6. In combination, a bracket, resilient means tending to raise said bracket, an adjustable stop limiting the raising of said bracket, a carrier mounted on said bracket 50 and adjustable horizontally thereon, a member pivoted on said carrier, a mercury switch carried by said member, and a vertically movable operating pin adapted to tilt said switch.

7. In combination, a bracket mounted pivotally at one end and resting upon a spring at the other end, an adjustable stop limiting the distance to which said spring can raise the bracket, a carrier adjustable longitudinally of said bracket, a member pivoted to said carrier, a mercury switch mounted on said member, a wear plate on said member adjacent the axis thereof, a vertically movable operating pin adapted to contact said wear plate, the center of gravity of said member 65 and parts carried thereby tending to main-

tain the switch in switch-closing position, and adjustable means limiting the distance to which the member can move in the switch-closing direction.

In testimony whereof I have hereunto signed my name to this specification.

EDWARD W. MENKE.
